UNITED STATES PATENT OFFICE.

GEORG MERKEL, OF MUNICH, GERMANY.

RETORT-DISCHARGER.

1,228,942.

Specification of Letters Patent. Patented June 5, 1917.

Application filed April 13, 1917. Serial No. 161,899.

To all whom it may concern:

Be it known that I, GEORG MERKEL, citizen of Germany, residing at Munich, Bavaria, Germany, have invented certain new and useful Improvements in Retort-Dischargers; and I do hereby declare the following to be a full, clear, and exact description of the invention, such as will enable others skilled in the art to which it appertains to make and use the same.

My invention relates to improvements in devices for the discharge of solid residue from continuously working, water-sealed distilling-furnaces and the object of my invention is to provide a discharger of the class referred to, permitting the delivery of the said residue without being immersed in and passed through the water.

I attain my object by the construction and combination of parts, as herein set forth and described and as illustrated on the drawing herewith which shows a vertical section of my improved device.

In distilling processes a seal is generally required for the complete exclusion of air and such a seal is particularly indispensable in continuously working distilling devices.

One way of effectively preventing access of air into the distilling compartment during the continuous discharge of the residue of the distilling process is the employment of a water-seal which is in many cases provided by immersing the bottom of a furnace-shaft in water and removing the material by means of an inclined screw conveyer, elevator or similar device.

These known contrivances have the great disadvantage that the material becomes saturated during its discharge. They therefore permit of employment only in those cases where even a considerable amount of water in the distilled residue is not detrimental, while they are useless wherever the chemical or physical nature of the product of distillation is such that the product would be harmed by wetting.

On the other hand it has been proposed to employ drums or cylinders having boxes or buckets for the continuous discharge of the residue. The known devices of this class are, however, incapable of preventing the entrance of air into the furnace; on the contrary, they cause the air present in the boxes or buckets to be forcibly driven into the distilling compartment by the very material they receive.

An additional drawback of these known devices is the occurrence of jammings and injuries to the material during its discharge, because ordinarily the pressure of a considerable layer of material bears heavily on the movable part or parts of the discharge-devices.

All of these several disadvantages are obviated by my invention, my improvements permitting the continuous and gentle discharge of the material without flooding it with water and without permitting any air to get into the distilling compartment.

To the bottom 1 of a distilling furnace any suitable contrivance may be attached which continuously delivers the material coming from the furnace. In the example shown in the drawing it comprises an ordinary rotatable scraper table 2 which is closed off air-tight against the outside by a jacket 3.

The material being put in rotary motion by the said scraper table 2 will be removed by a shovel-like scraper blade 4 from the table and through the closed chute 5 be fed into the delivery device. This device comprises a drum or cylinder 7, provided with buckets or boxes 6, said drum rotating in a casing composed of segmental portions 8, 9, 10. These segmental portions are larger than the openings of the buckets, so that the latter during the rotation of the drum or cylinder are amply covered. Preferably the upper segmental portions 8 and 9 may be shaped to form a socket 11 for connection with the chute 5.

The bottom segmental piece 10 may be attached to and in the drawing appears integral with the water-tank 12 in which about one-half of the drum 7 is immersed. Also the segmental piece 9 is partly immersed in the water. The outer faces of the buckets 6 make a sliding fit with the inner face of the casing 8-9-10, and the buckets extend the entire length of the casing, so that no water can escape from the tank 12 through the spout 16.

This segmental piece is connected by a pipe 13, above the water-level in the tank 12, with the socket 11.

The rotation of the bucket wheel 7 being in an anti-clockwise direction that is in a direction away from the water, the bucket which passes the water fills with water, while the air escapes. In position 14, indicated on the drawing by dotted lines, a bucket is shown as being entirely filled with water,

- which owing to the pressure of the atmosphere, remains within the bucket until the position 15 is reached, also indicated by dotted lines, that is, just before the bucket 5 reaches the mouth of pipe 13. On further rotation of the bucket-wheel the water commences flowing out of the bucket, because now the distilling gases from the furnace are permitted to enter through the pipe 13. 10 The bucket filled with the distilling gases then receives the material gliding down the chute 5 and discharges it on further rotation through the chute 16.
- Thus the buckets of the drum receive, during rotation, alternately water, distilling gases, the material intended for delivery, and air, and it will be understood that no air can be fed into the furnace by the delivery device, but, on the contrary, distilling 20 gases from the furnace are taken out of the same.
- I prefer to provide for the adjustability of the rotatory speed of the drum, to change the same whenever conditions require. Also 25 the scraper table may be so constructed as to permit of a precise regulation and control of the quantity discharged in order that the device may be so adjusted that the buckets are only partly filled with material and 30 jammings and injuries to the material during the discharge or delivery are thereby avoided.
- I claim:
1. A retort discharger comprising the combination with a furnace, of a chute in communication with the discharge end of said furnace, a bucket cylinder, a casing for the
- said cylinder having openings of different sizes in its wall, a tank, the said cylinder 40 and casing being partly within the said tank, and means of communication between the said casing, the tank and the furnace.
2. In a retort discharger, the combination with a furnace of a chute communicating 45 with its discharge end, rotary means for feeding material from the furnace into the chute, a casing in communication with said chute, said casing having spaced openings in its wall, buckets rotatable in said casing and 50 adapted to successively communicate with said openings, a tank adapted to contain liquid in which a part of said casing and certain of the buckets are immersed, and means establishing communication between 55 the tank, the casing and the chute.
3. In a retort discharger, the combination with a furnace of a chute communicating with its discharge end, means for feeding material from the furnace into the chute, 60 a casing connected to said chute and comprising segments with openings therebetween, buckets rotatable in said casing the openings of the buckets being smaller than any of said segments, a tank adapted to 65 contain liquid in which a part of said casing and certain of the buckets are immersed, and a pipe having ends opening into said chute and said casing.
- In testimony whereof I hereunto affix my 70 signature in the presence of two witnesses.
- GEORG MERKEL.

Witnesses:

EDUARD PASRID,
AUGUSTE FICHLER.
